PORTABLE DOOR LATCH

James Holland, Los Angeles, Calif.

Application December 26, 1934, Serial No. 759,221

1 Claim. (Cl. 292—292)

This invention relates to a door lock and particularly pertains to a portable latch therefor.

It is desirable when traveling and otherwise to provide simple and effective means which may be applied to a door and which will lock the door independently of any key operated locking means with which the door is equipped. This prevents the door from being opened from the outside and insure security and privacy for the occupant of a room. It is the object of the present invention to provide a simple and inexpensive latch structure which is of small compass, may be easily carried in the pocket or purse, and instantly applied to a door in an operative position without the use of tools, and will when the door is locked hold the door in its locked position until released from the inside of the door, and without the possibility of being moved or operated from the outside of the door.

The invention contemplates the provision of a wedge member and a keeper, the wedge being capable of being disposed in a position between the vertical edge of a door jamb and the vertical face of a door post, and to be forced into a position with relation to the post as the door is closed, the keeper being mounted upon the portion of the wedge member projecting into the room to be locked, and being capable of manipulation to move the keeper from an unlocked to a locked position with relation to the door, irrespective of whether or not the face of the door is flush or inset with relation to the door frame.

The invention is illustrated by way of example in the accompanying drawings in which:

Figure 1 is a fragmentary view in perspective showing the application of one form of the present invention to a door of the inset type and in an unlatched position.

Fig. 2 is a view in front elevation showing a fragmentary portion of a door and a door post showing one form of the latch structure in its locking position.

Fig. 3 is a view in plan showing the latch structure with the keeper indicated by solid lines in its locked position and by dotted lines in its unlocked position.

Fig. 4 is a view in perspective showing another form of the invention indicating the locked position of the keeper in dotted lines and the unlocked position in solid lines.

Fig. 5 is a view in perspective showing the invention with a different form of keeper and indicating the device with the keeper out of its locked position.

Fig. 6 is a view in vertical section showing the keeper in its locked position.

Fig. 7 is a view in perspective showing the wedge member and the keeper assembled in an inoperative position, such as would be the case when the entire latch device is to be carried in a pocket or purse.

Referring more particularly to the drawings, 10 indicates a jamb of a door 11 which is adapted to swing into a closed position with relation to a door frame, the post 12 of which is here shown. In some types of doors the face of the post will be flush with the face of the jamb of the door, and in that instance there would be no difficulty in applying a portable latch of the present character. Other doors, however, are made with an offset face 13 which causes the door to set in from the face so that the face 14 of the door jamb 10 will be in a different plane from the face 13 of the door post. In such cases the present device is particularly applicable, since its construction is such as to insure that the keeper may easily fit against the face 14 of the door jamb irrespective of the position of the face 13 of the door post. In the preferred form of the invention, as shown in Figs. 1, 2, 3, and 7 of the drawings, a wedge plate 15 is provided to assume an edgewise position between the contiguous faces 16 and 17 of the door jamb and post, respectively. This plate is relatively thin in width and has its greater sectional dimensions extending vertically. At the end of the plate 15 which occurs between the faces 16 and 17 of the door and the door frame a laterally extending blade 18 is provided. This blade is supposed to be forced into the wood of the face 17 of the post 12 as the door is closed, since the length of the blade 18 plus the thickness of the plate 15 is greater than the distance which normally occurs between the edge 16 of a door and the face 17 of a door post. In some instances it may be desirable to secure the plate 15 in position permanently, and for that reason screw holes 19 are provided to permit the plate to be screwed against the face 17 of the door post. The opposite end of the plate 15 from the end carrying the blade 18 projects into the room to be locked and projects beyond the face 14 of the door. Attention is directed to the fact that it is not necessary to satisfactory operation that this member project beyond the face 13 of the door post. This projecting end is hooked-shape as indicated at 20, and comprises a laterally extending portion 21 and an end portion 22 which

is bent parallel to the body of the plate 15 and extends toward the blade 18. The terminating edge of the member 22 is substantially in the plane of the face 14 of the door when the door 5 is closed. Mounted upon the hook portion 20 is a keeper 23. In Figs. 1 to 3, inclusive of the drawings, the keeper is shown as having an upper horizontal portion 24 with which legs 25 and 26 are integrally formed. A straight slot 10 27 occurs between these legs, the slot being of a width substantially equal to the thickness of the plate 15 so that the keeper may be moved upwardly and downwardly on the plate from a locking to a non-locking position and vice versa. 15 The leg 25 is substantially twice the vertical height of the section of the wedge plate 15. The lower end of the leg 25 is fitted with a laterally extending stop 28 which extends toward the leg 26 and stands in a partially obstructing position 20 across the bottom of the slot 27. Thus when the keeper is lifted to the top of its intended movement the stop 28 will engage the under side of the plate 15 and limit further lifting movement of the keeper. The leg 26 of the 25 keeper is of a length greater than the vertical height of the plate 15 but does not extend to the bottom thereof. This insures that the lower portion of the keeper will not stand in a bridging relation to the crank 29 which occurs between 30 the faces 16 and 17 of the door and the door frame, respectively. By this arrangement it is insured that a person on the outside of the door could not insert a thin instrument in the door crack 29 and engage the lower end of the keeper 35 to lift the keeper from its seat and its locking position. The portion of the leg 25 which extends below the plate 15 when the keeper is in its lower position is formed along its inner edge with a curved face 30 which makes it possible 40 for the keeper to be turned, using the lower portion of the leg 25 as an axis when the keeper has been raised to its uppermost position. By this arrangement it will be seen that when the 45 keeper is in its lowermost position and the curved face 30 is below the edge of the wedge plate 15 the keeper cannot be rotated.

In the form of the invention shown in Fig. 4 of the drawings the wedge plate 15 is provided but with it a different form of keeper is used. 50 This comprises a lower portion 31 which extends upwardly between the faces of the plate 15 and the rearwardly turned hooked portion 22, and when in its uppermost position is limited by a 55 T-shaped head 32 carried on its bottom end. When the T-shaped head 32 abuts against the lower face of the plate 15 the keeper member 31 is of a length to extend above the upper face of the plate 15 and to provide a pivot 33 for a 60 lock lug 34 which may be swung laterally to locking and non-locking positions. The lock lug 34 is formed at its free end with a T-shaped head 35 so that when the lug 34 is swung to a vertically aligned position with relation to the 65 keeper portion 31 the entire keeper structure may move downwardly until it hangs on the head 35. At such a time the lock will be inoperative.

In the form of the device shown in Figs. 5 70 and 6 of the drawings a variation of the structure shown in Fig. 4 is disclosed, although the same wedge plate 15 is provided. The keeper in this instance comprises a lower T head 36 carried at the bottom of a keeper bar 37 which is 75 of a length slightly in excess of twice the vertical

height of the wedge plate 15. An overhanging head portion 38 occurs at the upper end of the keeper bar 37 and is formed integral with a downwardly projecting member 39 spaced from the bar 37 to form an intermediate slot 40 of a 5 width slightly in excess of the thickness of the wedge plate 15. The member 39 has an offset extension 41 which may project downwardly between the plate 15 and its hooked portion 22 as clearly shown in Fig. 6 of the drawings. Here 10 it will be seen that the space between the plate 15 and the hooked portion 22 is substantially equal to the combined widths of the bar 37, the slot 40, and the extension 41. A shoulder occurs between the main portion of the member 15 39 and the extension 41 as indicated at 42. When the keeper is not in a locked position the keeper rests upon this shoulder as clearly shown in Figs. 5 and 6. When the keeper is to be placed in a locking position the keeper is lifted 20 and moved sideways until the bar 37 and the extension 41 will straddle the plate 15 after which the keeper may be moved downwardly to the locking position indicated by dotted lines in Fig. 6.

In operation of the present invention, and referring particularly to the form of the device shown in Figs. 1 to 3, and 7, inclusive, it will be seen that when the structure is not in use the keeper may be nested within the plate 15 as indicated in Fig. 7, and that afterwards the parts may be separated and assembled as shown in Figs. 1 and 2. When the keeper 23 has been mounted upon the wedge plate 15 it is preferably disposed with its major width lying in a plane parallel to that in which the plate 15 lies with the short leg 26 of the keeper extending outermost. When in this assembled relation, as shown particularly in Fig. 1, the plate 15 may be extended horizontally across the face 17 of the door post until the inner edge of the member 22 of the plate hook 20 abuts against a face 13 of the door post, whether this face is inset or flush. The door may then be closed. The face 16 of the door jamb will then engage the smooth back face of the plate 15 and will force the blade 18 into the face 17 of the door post. This will hold the plate against removal. If, however, it is considered desirable to maintain the plate in its mounted position screws may be passed through the openings 19 and into the door post. After the plate has been positioned in engagement with the door post and the door has been closed the keeper 23 may be moved to a locking position by first lifting the keeper while it is in the aligned position shown in Fig. 1, and as indicated by dotted lines in Fig. 3, and then rotating the keeper until it is in a transverse position, as shown by solid lines in Fig. 3. The keeper may then be moved downwardly again with the legs 25 and 26 straddling the plate 15. The upper bar 24 of the keeper will bridge the crack of the door and will hold the keeper so that the door cannot be opened since the keeper obstructs its movement. When it is desired to unlock the 65 door the keeper is lifted and then rotated, after which the door will swing clear of the plate 15. In the form of the device shown in Fig. 4 the plate is installed in the same manner as previously described, and normally the keeper is disposed 70 with its two members 31 and 34 in vertical alignment and in their lowermost position hanging from the head 35. When it is desired to lock the door the keeper may be drawn upwardly until a pivot 33 clears, after which it may be 75

swung to a lateral position in a manner to stand in an obstructing position and prevent the door from being opened. In the form of the invention shown in Figs. 5 and 6 of the drawings the keeper is originally in the position shown in Fig. 5 so that the door might swing along the flat back face of the plate 15, after which the keeper may be lifted and moved over to straddle the plate 15 and to drop downwardly to a locking position.

It will thus be seen that the lock here disclosed is quite simple in its construction, being made of two parts which may be easily assembled for operation, and readily applied to and removed from locking position with relation to a door.

While I have shown the preferred form of my invention, as now known to me, it will be understood that various changes might be made in the combination, construction, and arrangement of parts, by those skilled in the art, without departing from the spirit of the invention as claimed.

Having thus described my invention what I claim and desire to secure by Letters Patent is:

A portable door latch including a wedge mem-

ber in the form of a flat plate having adjacent to one end a transversely disposed blade and having at its other end an angular portion and a reverting extension on said angular portion terminating in a free edge and spaced from and 5 paralleling the plate to form with the same a squared socket open at one side toward the blade end of the plate, and a keeper plate having a pair of legs and a portion connecting said legs at one end and spacing the same apart, one of said 10 legs being squared and of a size to slidably inter-fit lengthwise of the squared socket of the wedge plate when the latch is in operative position, the space between said legs adapting the keeper to selectively straddle the upper edge of the wedge 15 plate and the said angular portion thereof in use, and the keeper plate being of a thickness to nest flatwise against the wedge plate with one end thereof extending beneath the said reverting extension and into the socket through the open 20 side of the latter when the latch is removed from operative position.

JAMES HOLLAND.
